UNITED STATES PATENT OFFICE.

KARL SCHÄFFERKÖTTER, OF PRÜM, GERMANY.

EXPLOSION-ENGINE.

SPECIFICATION forming part of Letters Patent No. 731,507, dated June 23, 1903.

Application filed June 28, 1902. Serial No. 113,637. (No model.)

To all whom it may concern:

Be it known that I, KARL SCHÄFFERKÖTTER, a subject of the Emperor of Germany, residing at Prüm, Trier, Prussia, Germany, have invented certain Improvements in Explosion-Engines, of which the following is a specification.

In explosion-engines after a long stop the inconvenience arises that the cold air in the cylinder of the machine prevents the explosive mixture from readily entering the said cylinder when said machine is to be started. This invention affords means and comprises a device for evacuating said cylinder, so that the air is drawn out and the mixture is readily received within the vacuum.

The accompanying drawing illustrates the invention by a diagrammatical view of the device.

20 In the construction of my invention I use an ordinary air-pump *a*, which is connected by a pipe *b*, having two branches *c* *c'*, to both ends of the cylinder *d* of the motor, thus providing means for evacuating the air 25 on both sides of the piston *e*. The purpose in view in having the pipe *b* branched for communicating with both ends of the cylinder is to allow complete evacuation of the said cylinder for obtaining a ready working 30 of the piston therein when the latter is operated. Valves *f* and *f'* on said two branches adjacent to the cylinder normally close the pipe and its branches from said cylinder. The said valves are opened and closed by 35 means of two arms *g* and *g'*, which are parallelly connected with each other by two bars *h* *h'*, pivoted thereto, so as to guide said arms parallelly to each other. A non-return valve *i* is inserted at the lower end of the air-pump 40 *a* between said pump and pipe *b*, and a clack-valve *k* in the piston of said pump allows the air to be discharged therethrough when the pump is operated.

It will be clear that the hereinbefore-described device is supplemental to the normal admission and exhaust ports (shown at *l* and *l'*) and is independent thereof.

The operation of this device is as follows:

When the machine is to be started, the valves *f* *f'* are opened by lifting the bar *h*, 50 which may be secured in the lifted position in any suitable manner. (See the position as indicated in dotted lines.) Now the air is evacuated from the cylinder by operating the air-pump, whereby the explosive mixture is 55 compelled to readily enter the cylinder, so that a failure of ignition is excluded.

It will be clear that in self-propelled vehicles the bar *h* and the pipe *b* may be easily so formed and arranged that the device may 60 be operated from the driver's seat, thus affording means for insuring the operation of the engine at all times and to set the latter in motion with the least possible loss of time.

Having now described my invention, I 65 claim—

1. In an explosion-engine, the combination with the motor-cylinder having the normal admission and exhaust ports of an air-pump, a pipe connection between said pump and 70 both ends of said cylinder, valves for opening and closing said pipe connection adjacent to said cylinder, which valves are independent of said normal admission and exhaust means and supplemental thereto, and 75 means for operating said valves, substantially as described.

2. In an explosion-engine, the combination with the motor-cylinder having the normal admission and exhaust ports of an air-pump, 80 a pipe connection between said pump and both ends of said cylinder, valves for opening and closing said pipe connection, said valves being supplemental to said admission and exhaust means, and a non-return valve 85 between said pump and pipe, a clack-valve in the piston of said pump and means for simultaneously operating said valves in the pipe connection independently of said admission and exhaust means, substantially as 90 and for the purpose described.

KARL SCHÄFFERKÖTTER.
